CLAIM

The ornamental design for a payout tube, as shown and described.

DESCRIPTION

FIG. 1 is a perspective view from the top and side of a payout tube, which can be used for a wound coil of wire. FIG. 2 is a perspective view from the bottom and side of the payout tube of FIG. 1.

FIG. 3 is a front view of the payout tube of FIGS. 1 and 2. FIG. 4 is a back view of the payout tube of FIGS. 1 and 2. FIG. 5 is a left side view of the payout tube of FIGS. 1 and 2.

FIG. 6 is a right side view of the payout tube of FIGS. 1 and 2.

FIG. 7 is top view of the payout tube of FIGS. 1 and 2; and, FIG. 8 is a bottom view of the payout tube of FIGS. 1 and 2.

The broken lines in the figures are for the purpose of illustrating unclaimed portions of the system or environmental structure or boundaries of the claim and form no part of the claimed design.

1 Claim, 7 Drawing Sheets
